(74) Attorney, Agent, or Firm — Birch, Stewart, Kolasch & Birch, LLP

(57) **CLAIM**

The ornamental design for a laptop computer, as shown and described.

DESCRIPTION

1. Laptop computer

1.1 : Top perspective, shown in a closed configuration

1.2 : Front, shown in a closed configuration

1.3 : Back, shown in a closed configuration

1.4 : Left, shown in a closed configuration

1.5 : Right, shown in a closed configuration

1.6 : Top, shown in a closed configuration

1.7 : Bottom, shown in a closed configuration

1.8 : Top perspective, shown in an open configuration

1.9 : Front, shown in an open configuration

1.10 : Back, shown in an open configuration

1.11 : Left, shown in an open configuration

1.12 : Right, shown in an open configuration

1.13 : Top, shown in an open configuration

1.14 : Bottom, shown in an open configuration

1.15 Bottom perspective, shown in a closed configuration, showing a state of use

The parts shown by means of broken lines in the reproductions are not part of the claimed design.

1 Claim, 15 Drawing Sheets
